BOAT HULL CONSTRUCTION

Robert R. Steele, Jr., Duluth, Minn.

Application September 30, 1938, Serial No. 232,550

3 Claims. (Cl. 114—78)

This invention relates to boat hull construction and the embodiment here illustrated is especially designed and adapted for use in the building of smaller craft such as sailing boats, power boats, or combinations of both, as employed for pleasure purposes.

The principal objects of the invention are lightness of construction with maximum strength and safety factors, together with low cost, simplicity, and speed of construction, the same being especially adapted for use in the union of parts as by welding, or the like.

In the practice of the invention I contemplate the use of light sheet metal, such as aluminum alloys, steel, or other well known composition sheet material such as "Weldwood" or the like.

Referring to the accompanying drawing, forming part of this application, and wherein like reference characters indicate like parts:

Figure 1 is an elevation of the fore and aft bulkhead of a sailboat, constructed in accordance with the invention.

Figure 2 is a plan view of the interior of a sailboat in which the invention is employed.

Figures 3, 4, 5, 6, 7, 8 and 9 are transverse sections taken on the lines as projected from Figures 1 and 2.

It is to be understood that the material used is as light and thin as possible consistent with the objects sought, thus the incidental novel cellular arrangement is provided for accomplishing the necessary strength, together with rigidity of the assembled fabricated structure, which latter is not found in the ordinary wooden hull construction.

The embodiment here illustrated is that of the invention as applied to the hull of a racing sail boat and wherein 1—1 represent two spaced fore and aft bulkheads shaped to the buttock plane of the boat, their centermost portion being deeper as at 2 so as to form the opposite sides of the trunk cabin 3 if desired and may also form the side walls of the cock-pit 4, the quarter berths 5, the transom berths 6, the lockers 7, the toilet locker 8, the hanging space 9, galley drawers, locker, etc., 10, and the sail bins 11, thus forming the desired cellular hull, with but little additional structure necessary to complete the full complement of compartments for such a vessel.

At 12 I have illustrated in dotted lines a narrow strip along the upper edge of the central deeper portion of each longitudinal bulkhead plate 1 which in the figures from 3 to 9 inclusive is shown as being bent over forming a

flange to which the deck 13 of the trunk cabin is attached, and at 14, both fore and aft of the trunk cabin, a similar flanged portion of each bulkhead 1 is provided for the reception of the deck 15 of the hull.

At 16 along the major portion of the lower edge of these bulkhead plates they are flanged normal to the shell for convenience in welding thereto and thus avoid the more difficult acute angle that would result were the plates extended straight down to the skin.

The athwartship sectional bulkheads 17 are welded along their inner edge and to their respective fore and aft bulkhead upon either side of the hull, and any desired number of longitudinal frame member 18 are welded to the bulkheads 17, thus completing the frame structure of the boat, and in the larger compartments for example, 5, 6 and 11, the skin or outer shell is shown as reinforced by frame like members 19, they being plain flat bars, similar to those illustrated at 18, and welded along one of their edges to the shell.

In this construction the usual molds and ribbands are dispensed with, as well as the ordinary engine foundation if any, but as indicated at 21, the latter may be attached directly to the fore and aft bulkheads 1—1, thereby simplifying the construction; the location of the engine being indicated at 21 in Figure 2.

Having thus described my invention, what I claim and desire to secure by Letters Patent, is:

1. In a ship's hull construction, the combination comprising a hull having an exterior skin, spaced preformed longitudinal bulkheads, one upon either side of the longitudinal center of the ship the entire length thereof and conforming in size and shape to the longitudinal section of the ship at the plane in which it is placed, spaced preformed transverse bulkheads extending from the outside of the longitudinal bulkheads to the skin of the ship and secured along their edges thereto and forming therebetween the various compartments of the ship, said longitudinal bulkheads having spaced preformed openings therein providing access to and forming the entrances to said compartments.

2. In a ship's hull construction, the combination comprising a hull having an exterior skin, interior compartments, and a centrally disposed trunk cabin, spaced preformed longitudinal bulkheads forming the hull girder strength and one wall of all compartments and said trunk cabin, one of said longitudinal bulkheads being positioned upon either side of the longitudinal

center of the ship the entire length thereof and conforming in size and shape to the longitudinal section of the ship at the plane in which it is placed, spaced preformed transverse bulkheads 5 secured along one edge to the outside of the longitudinal bulkheads and extending to the skin of the ship and secured along their outer edges thereto and forming therebetween the various interior compartments of the ship, said 10 longitudinal bulkheads having spaced preformed openings therein forming the entrances to said compartments.

3. In a ship's hull construction, the combination comprising a hull having an exterior skin 15 and a deck, longitudinal bulkheads, one upon

either side of the longitudinal center of the ship, the entire length thereof, preformed to conform in size and shape to the longitudinal section of the ship at the plane in which it is placed and extending above the deck, transverse bulkheads 5 extending at spaced intervals from the outside of the longitudinal bulkheads to the skin of the ship and secured along their edges thereto and forming therebetween the various below deck compartments of the ship, said deck extending from the outside of the longitudinal bulkheads 10 over the tops of the transverse bulkheads to the skin of said ship.
